By Robert G. Phillips,
Attorney.

UNITED STATES PATENT OFFICE.

FREDERICK SIGRIST, OF KINGSTON-ON-THAMES, ENGLAND.

STRUT, SPAR, OR THE LIKE FOR USE IN AIRCRAFT CONSTRUCTION.

1,303,507.

Specification of Letters Patent.

Patented May 13, 1919.

Application filed October 10, 1917. Serial No. 195,809.

To all whom it may concern:

Be it known that I, FREDERICK SIGRIST, a subject of the King of Great Britain and Ireland, residing at Kingston-on-Thames, in the county of Surrey, England, have invented a new and useful Improvement in Struts, Spars, or the like for Use in Aircraft Construction, of which the following is a specification.

10 This invention relates to struts, spars or the like used in the construction of aeroplanes and other aircraft, and it consists in reinforcing such members when made of wood by one or more longitudinally arranged metallic ribs which extend through both the length and the thickness or depth of said strut or spar, the object being to stiffen such struts, spars or the like so that they are able to stand the stresses imposed upon 20 them equally as well as metallic struts or spars of tubular construction.

In the accompanying drawing which illustrates this invention:—

Figure 1 is a view in transverse section of 25 a strut constructed according to the present invention,

Fig. 2 is a broken view in plan of an alternative construction, and

Fig. 3 is a broken view in transverse section showing an alternative construction.

Throughout the views similar parts are marked with like letters of reference.

The wooden strut—which has any desired exterior shape—is formed of two pieces a and a^1 which on being fixed together edge to edge, form the complete strut. Between these two pieces is placed a metallic rib the depth of which is the same as the thickness or depth of the strut and the length of same 40 is such that it extends through the whole length thereof. The metallic rib is formed of two channel-shaped plates b which are fitted over the inner edges of the pieces a and a^1 , the horizontal flanges b^1 being let into said pieces so as to preserve the smooth exterior surfaces of the strut.

The various elements of the strut are held and fixed together either by means of a series of transverse tie bolts c^1 as shown in Fig. 1 50 or by wrapping the two pieces a and a^1 , when

in position to form the complete strut, with a tape e or the like of any suitable material as shown in Fig. 2. In the former construction the head c^1 of the bolt c is suitably shaped to preserve the outline of the rear edge of the strut and the nut c^2 of said bolt is suitably recessed in the front edge of the strut to the same end.

The channel-shaped plates b may be individually secured to the two pieces a and a^1 by screws or the like.

Although the construction hereinbefore described is what I think is the preferable construction I do not limit myself to the use of a reinforcing rib constructed out of two pieces of channel section as it would be within the spirit and scope of this invention to so combine said two pieces of channel section as to make an H-shaped rib as shown in Fig. 3 which in effect it becomes when two channel-shaped plates are employed and all the elements of the strut are fixed together.

What I claim as my invention and desire to secure by Letters Patent is:—

1. A strut, spar or the like for use in the construction of aircraft, comprising two pieces of wood adapted on being placed edge to edge to give the desired exterior shape to the strut, spar or the like, a metallic rib of a double channel section located between said pieces and extending through both the length and the depth or thickness of the strut or spar, and means for fixing and holding said elements together.

2. In a strut, spar or the like for aeroplanes and other aircraft, the combination of two strips of wood adapted to be placed edge to edge, a channel-shaped metallic plate adapted to fit on the inner edge of each strip, and means for fixing and holding said elements together.

3. In a strut, spar or the like for aeroplanes and other aircraft, the combination of two strips of wood adapted to be placed edge to edge, a metallic rib of H-section located between the abutting edges of the two strips, and means for fixing and holding said elements together.

4. A strut, spar or the like for use in

the construction of aircraft, comprising two strips of wood a and a^1 adapted on being placed edge to edge to give the desired exterior shape to the strut, spar or the like, 5 a metallic rib b of girder section located between said strips and extending through both the length and the depth or thickness

of the strut or spar, and a series of longitudinally arranged tie bolts c for holding the elements of the strut or the like together. 10

In testimony whereof I have signed my name.

FREDERICK SIGRIST.
